UNITED STATES PATENT OFFICE.

JAMES COMLY, OF PHILADELPHIA, PENNSYLVANIA.

DESIGN FOR BOXES.

Specification forming part of Design No. 7,849, dated November 10, 1874; application filed July 31, 1874.
[Term of Patent 3½ years.]

To all whom it may concern:

Be it known that I, JAMES COMLY, of the city and county of Philadelphia, and the State of Pennsylvania, have invented a new and useful Design for a Box; and I do hereby declare the following to be a clear and exact description of the nature thereof, sufficient to enable others skilled in the art to which my invention appertains to fully understand, make, and use the same, reference being had to the accompanying drawings making part of this specification, in which—

Figures 1 and 2 are views of two sides of the box embodying my invention. Fig. 3 is a top view thereof.

Similar letters of reference indicate corresponding parts in the several figures.

My invention relates to a design for a box, which is fully illustrated in the accompanying drawings, to which reference is made.

a represents the body of the box, which is of the form of a house. The top of the house is occupied by gables *b b b b*, which are con-

tinuous of and adjoin each other, and of which there is one for each side of the body.

It will be seen that each side has a gable centrally, and as the several gables adjoin and are continuous they constitute the entire roof of the house, there being no roof proper between the gables, so that the tops of the backs of the gables are at the central point of the roof, whereby the design shows large and well-marked gables on a small house.

Projecting upwardly from the central point of union of the gables is a pinnacle, *c*.

What I claim as my invention is—

The design for a box of house form, having a gable, *b*, centrally at each side, the several gables being continuous of and adjoining each other, and constituting the entire roof of the house, as shown and set forth.

JAMES COMLY.
